UNITED STATES PATENT OFFICE.

WILLIAM F. MUEHL, OF SYRACUSE, NEW YORK.

OXYGEN-GENERATOR.

1,160,524.

Specification of Letters Patent. Patented Nov. 16, 1915.

Application filed December 12, 1914. Serial No. 876,835.

To all whom it may concern:

Be it known that I, WILLIAM F. MUEHL, a citizen of the United States, residing at Syracuse, in the county of Onondaga and 5 State of New York, have invented certain new and useful Improvements in Oxygen-Generators, of which the following is a specification.

My invention relates to a process of and 10 apparatus for generating oxygen and supplying the same to the cylinder or cylinders of internal combustion engines, for removing carbon deposits therefrom.

An important object of the invention is 15 to provide means to generate oxygen and supply the same to the interior of the cylinder or cylinders of an internal combustion engine for removing deposits of carbon from the same in a highly efficient manner.

20 A further object of the invention is to provide novel and simple electrically operated means to heat the chemical or chemicals contained within the apparatus for generating the oxygen.

25 A further object of the invention is to provide apparatus of the above mentioned character, which is portable, and having means whereby the electrically operated heating apparatus embodied therein may be readily 30 connected with the ordinarily available source of current.

Other objects and advantages of the invention will be apparent during the course 35 of the following description.

35 In the accompanying drawings forming a part of this specification and in which like numerals are employed to designate like parts throughout the same, Figure 1 is a central longitudinal sectional view through 40 apparatus embodying my invention, parts thereof being broken away, Fig. 2 is a similar view through the chemical holding and heating apparatus, Fig. 3 is a similar view through one of the couplings, and Fig. 4 is a central longitudinal sectional view through a 45 slightly different form of apparatus.

In the drawings, wherein for the purpose 50 of illustration is shown a preferred embodiment of my invention, (attention being called first to Figs. 1 to 3 inclusive), the numeral 5 designates a preferably vertical oxygen holding tank or shell having its lower end rigidly mounted upon supports or feet 6, as shown. Attached to the upper 55 closed end of the tank 5 is a safety pressure-relief valve 7, of any well known or pre-

ferred type. Connected with this end of the shell 5 near and spaced from the valve 7 is a compound valve-structure 8, having a needle valve 9, to regulate the passage of oxygen therethrough in proper amounts, and an auxiliary valve 10, which is adapted to be moved to complete open or closed positions. Connected with the valve-structure 8, between the valves 9 and 10, is a branch pipe 11, having a pressure gage 12 connected therewith, for indicating the pressure within in the tank 5, as shown. Connected with the upper end of the valve-structure 8 is an outlet pipe 13, for a purpose to be described.

The tank 5 is provided in its bottom with a centrally arranged opening 14, receiving an interiorly screw-threaded ring 15, having a laterally extending annular flange 16, which is bolted or otherwise rigidly attached to the bottom, by means of bolts 17 or the like.

The numeral 18 designates an oxygen generating receptacle or shell, which is substantially cup-shaped, with its upper end open 80 and its lower end closed by a relatively thick head or bottom 19, having its exterior screw-threaded, as shown at 20, and provided with a stop-flange, as shown at 21. The head 19 screw threads into the ring 14, 85 as is obvious, with the stop-flange engaging the ring 15, as shown.

The receptacle 18 is heated by means of a resistance coil 22, the opposite ends of which are connected with wires 23 and 24. The 90 wire 24 is electrically connected with a screw-threaded sleeve-terminal 25, while the wire 23 is electrically connected with an end-terminal 26, connected with and insulated from the head 19, as shown.

The numeral 27 designates a socket of the ordinary type, adapted to be screw-threaded into the sleeve-terminal 25, whereby the terminals of the socket have electrical engagement with the terminals 25 and 26, 100 for completing the circuit, as is well known. Connected with the pipe 13 is a pipe 28, having connection with an oxygen distributing shell 29, having branch pipes 30 connected therewith, the same being adapted 105 for connection with the several cylinders of the engine. Connected with the outlet end of each branch pipe 30, as shown in Fig. 3, is a valve-controlled coupling 31. This valve-controlled coupling comprises a 110 casing 32, having screw-threaded engagement with a sleeve 33, apertured for receiv-

ing a tube 34, provided with a flanged head 35. In this manner the shell 31 has a swiveled connection with the tube 34, and forms a gas tight joint therewith. The 5 tube 34 is suitably connected with the outlet end of the pipe 30, as shown. The tube 34 has its outlet end internally screw-threaded, for receiving a screw-threaded sleeve 36, having engagement with a coil spring 37, enabling 10 a ball-valve 38, adapted to engage and disengage a valve seat 39. This ball-valve opens downwardly to permit of the free passage of the oxygen into the casing 32, but automatically seats upon the passage 15 of the oxygen or other gases in a reverse direction. The shell or casing 32 has its free end screw-threaded, as shown at 40, and is adapted to be inserted within the screw-threaded spark-plug receiving opening 20 of the cylinder of the engine. The shell 32 is provided with a transverse opening 41, receiving a rotatable valve 42, by means of which the supply of oxygen into the cylinder may be regulated, and completely cut 25 off when desired.

The form of apparatus shown in Fig. 4, comprises a tank 44, closed at its bottom and provided at its top with a large screw-threaded opening 45, engaging with a removable screw-threaded cap or plug 46, as shown. Attached to the lower side of the cap or plug 46 and depending therefrom is a tube 47, to which is secured a chemical receiving and heating receptacle 48, clamped thereto by means of a nut 49, having screw-threaded engagement with the tube. This tube is formed of insulating material and receives lead wires 50, the lower ends of which pass out through apertures in the 40 tube 47 and have electrical connection with a heating coil 51, surrounding the tube 47 within the shell 48. This heating coil 51 is preferably surrounded by a protecting casing 52. The lead wires 50 extend into a 45 stationary socket element 53 and are there connected with the socket element terminals. The numeral 54 designates a removable co-acting socket element, adapted to electrically connect the lead wires 50 with a source of current. The cap or head 46 has connection with a gas outlet pipe 55, communicating with the interior of the tank 44 through a port 56 or the like. This pipe 55 has a cut-off valve 57 connected therein. 50 The pipe 55 is connected with the pipe 28, which is adapted to be connected with the cylinder or cylinders of the engine, as already described. Connected with the pipe 55 inwardly of the cut-off valve 57 is a 55 branch pipe 59, having a pressure gage 60, as shown.

In the use of the apparatuses, in practising the process, the chemical or chemicals

from which the oxygen is generated, such 65 for example as potassium chlorate and manganese dioxide, are placed within the oxygen generating receptacle and the receptacle placed in the outer tank. The current is turned on for heating the receptacle whereby 70 the oxygen is liberated, the same being held within the outer tank. It is preferred to generate the oxygen while the same is being used in order that it may be supplied to the cylinder or cylinders, in a warm condition. I have found that the oxygen is very 75 effectual in removing carbon.

It is to be understood that the forms of my apparatus shown and described are to be taken as preferred examples of the same, 80 and that various changes in the shape, size, and arrangement of parts may be resorted to without departing from the spirit of the invention or the scope of the subjoined claims.

Having thus described my invention what 85 I claim is:—

1. In apparatus of the character described, a gas holding tank provided with an opening in its top, a removable head to cover the opening, a chemical holding and heating receptacle depending from the head and adapted to be arranged within the tank, and electrically operated heating means arranged in proximity to the receptacle to heat the material therein. 95

2. In apparatus of the character described, a gas holding tank having an opening in the top thereof, a tube connected with the head and depending therefrom into the tank, a chemical receiving and heating shell connected with and supported by the tube within the tank, an electrically operated heating device arranged in proximity to the receptacle, circuit wires connected with the electrically operated heating device and passing through the tube, and a gas outlet conduit leading into the tank. 105

3. In apparatus for generating oxygen, a gas holding tank provided in one end with an opening, a removable head to cover the opening, a chemical holding and heating receptacle carried by the head and adapted to be arranged within the tank, electrically operated heating means arranged in proximity to the receptacle and carried thereby, 110 and contact elements arranged upon the outer side of the head and electrically connected with the electrically operated heating means. 115

In testimony whereof I affix my signature 120 in presence of two witnesses.

WILLIAM F. MUEHL.
